DISPLAY PANEL FOR CIGARETTE VENDING MACHINES OR THE LIKE

Walter L. Koch, Caldwell, N.J., assignor to Automatic Canteen Company of America, Chicago, Ill., a corporation of Delaware

Filed Feb. 14, 1964, Ser. No. 78,631

Term of patent 14 years

(Cl. D52—3)

FIGURE 1 is a front elevational view of a display panel for cigarette vending machines embodying my new design;

FIGURE 2 is a sectional view thereof taken along the line 2—2 of FIGURE 1.

FIGURE 3 is a fragmentary outline sectional view thereof taken along the line 3—3 of FIGURE 1.

FIGURE 4 is a perspective view thereof.

The dominant features of the design reside in the portions shown in full lines.

I claim:

The ornamental design for a display panel for cigarette vending machines or the like, substantially as shown and described.
